(57) **CLAIM**

The ornamental design for an electroporation device screen with pattern, as shown and described.

DESCRIPTION

FIG. 1 is a front elevation view of an electroporation device screen with pattern in a first stage, showing the new design; FIG. 2 is a front elevation view thereof in a second stage; FIG. 3 is a front elevation view thereof in a third stage; FIG. 4 is a front elevation view thereof in a fourth stage; FIG. 5 is a front elevation view thereof in a fifth stage; FIG. 6 is a front elevation view thereof in a sixth stage; FIG. 7 is a front elevation view thereof in a seventh stage; and,

FIG. 8 is a front elevation view thereof in an eighth stage. The broken lines depict portions of the electroporation device screen that form no part of the claimed design. The appearance of the transitional image sequentially transitions between the images shown in FIGS. 1-8. The process or period in which one image transitions to another image forms no part of the claimed design.
